UNITED STATES PATENT OFFICE

2,521,063

TWO-TEMPERATURE REFRIGERATOR

Herman W. Kleist, Chicago, Ill., assignor to Dole
Refrigerating Company, Chicago, Ill., a corpora-
tion of Illinois

Application March 29, 1946, Serial No. 658,322

1 Claim. (Cl. 62—95)

1

My invention relates to an improvement in refrigerators and has for one purpose to provide refrigeration means for a domestic refrigerator.

Another purpose is to provide an improved two temperature refrigerator.

Another purpose is to provide a refrigerator including improved freezing means for a low temperature storage space.

Other purposes will appear from time to time in the course of the specification and claim.

I illustrate the invention more or less dia-
grammatically in the accompanying drawings
wherein:

Figure 1 is a vertical section;

Figure 2 is a section on the line 2—2 of Figure 1; and

Figure 3 is a plan view of the plate structure illustrated in the lower storage compartment of Figures 1 and 2.

Like parts are indicated by like symbols throughout the specification and drawings.

Referring to the drawings I illustrate in Figures 1 and 2 a conventional domestic refrigerator having side walls 1 and 2, a top wall 3, a bottom wall 4, a rear wall 5 and a horizontal partition wall 6. These six walls together define an upper storage chamber generally indicated as A and a lower storage chamber generally indicated as B. Each chamber has a forward opening or open side closed by insulated doors 7 and 8. It will be understood that the details of the insulation and of the walls do not of themselves form part of the present invention. I illustrate the compartments A and B as lined by any suitable sleeves 9 and 10 which may be of sheet metal or other suitable material. It will be understood that any suitable means may be employed for preventing heat transfer from the outside of the refrigerator to the sleeves 9 and 10. I may use for example a break in the material. Since such means do not of themselves form part of the invention, they are not indicated in the drawings, it being understood that any suitable type of insulated walls and door may be employed, to reduce heat transfer to a minimum.

The above described refrigerator housing may be mounted on or include a bottom structure having supporting legs 12 and side members 13 surrounding and defining a work chamber generally indicated as C. The work chamber C may be partially open, to permit free circulation of air.

In the work chamber I illustrate more or less diagrammatically a refrigerator unit including a base 15, a compressor 16, a motor 17, a condenser coil 18 and a receiver 19. 20 indicates a low side or suction line extending to the low

2

pressure side of the compressor 16. 21 is a high pressure duct extending from the compressor 16 to the condenser coil 18. 22 is a duct extending from the condenser coil 18 to the receiver 19, and 23 indicates a high pressure liquid line along which liquid refrigerant may be delivered from the receiver 19. The motor 17 may drive the compressor 16 for example through a belt 24. It will be understood that the unit thus described is indicated diagrammatically and any suitable means may be employed for receiving low pressure, evaporated refrigerant, and for delivering high pressure liquid refrigerant.

As means for withdrawing heat from the stor-
age chambers A and B I illustrate a plurality
15 of cold plates, preferably of the vacuum type. It
will be understood that I prefer to employ the
upper chamber A as a relative high temperature
storage chamber where the temperature never
reaches as low as the freezing temperature of
water. The chamber B is employed as a cold
storage chamber in which materials may be
frozen and stored in frozen condition. The tem-
perature therein may be as low as 0° F. or lower.

20 In the lower chamber B I illustrate a battery
or group of plates 25, herein shown as three in
number and as arranged in parallel horizontal
planes, the plates 25 being spaced apart suffi-
ciently to provide adequate intermediate storage
space. The plates may be spaced for example
30 by a plurality of supports 26 which may be posi-
tioned closely adjacent to the face of liner or
sleeve 10, to provide a minimum loss of storage
space. Each plate includes spaced horizontal
walls 27 and 28, the walls 28 having surrounding
35 circumferential flanges 29 which are sealed to
the wall 27 to provide a space which is closed
and which is preferably liquid and gas tight.
In this space I employ any suitable evaporator
coil 30. The space between the walls 27 and 28,
40 and about the coil 30 is preferably partially
filled with a suitable eutectic, to provide a hold-
over or storage feature. I may also employ any
suitable pressure fitting 31, through which the
interior of the plate may be partly evacuated in
45 such fashion that the outside atmospheric pres-
sure is effective to hold the walls 27 and 28 firmly
against the coil 30, in adequate heat exchange
relationship. It will also be seen that any spacing
means or fins may be employed if necessary, al-
50 though I find it advantageous, in general, to
employ relative thin plates, with the walls 27 and
28 held, by the above mentioned pressure dif-
ferential in intimate contact with the enclosed
evaporator coil 30.

55 In the device as shown liquid refrigerant, at
high pressure, is delivered through the duct 23 to

any suitable pressure reducing device 22. It passes thence by the duct 33 to the lowest plate 25, in the low temperature compartment B. After passing through the evaporator coil of the lowest plate, it flows through the duct 34 to the evaporator coil of the intermediate plate. Thence after passing through the evaporator coil of the intermediate plate it flows through the duct 35 to the coil of the top most plate 25. Thence the refrigerant flows through a duct 36, which may be embedded through part of its length in the intermediate partition 6. It is used to deliver the refrigerant, not yet fully evaporated, to the top of a vertically disposed plate 37, which is shown as dividing the upper compartment A into two divisions. The duct 36 delivers the refrigerant to the coil of the plate 37 and the refrigerant, after it has passed through the refrigerant coil of the plate 37, returns through the suction duct 38 to the suction line 20 and thence back to the low side 20 of the compressor 16. It will be understood that the plate 37 may be identical with the plates 25, but I may find it preferable under some circumstances to omit the eutectic and to employ what I may call a dry plate in the upper compartment A. At each side of the plate 37 I illustrate mesh or open work partitions 40 which space the stored material from actual contact with the faces or walls of the plate 35. 41 are any suitable and preferably removable shelves which may also be of open mesh material and which rest on any suitable supports 42 on the liner or sleeve 9 and corresponding supports 42 on the mesh walls 40.

It will be realized that I may employ other plates than the vacuum plates herein shown, but I find that vacuum plates of the type herein described are practical and adequate, and efficient in use.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows:

I illustrate a two-temperature cabinet in which readily applicable and readily removable cooling plates are employed. The parts are preferably so in proportion that the plates may be readily inserted through the apertures closed by the doors 7 and 8 and, on being disconnected from the various ducts herein shown, can readily be removed.

I find it advantageous to group or connect the plates which cool the lower compartment B as a unit, connected by the side supports 26. I may provide any suitable means for controlling the temperature of the device, but I preferably do this by employing a thermally responsive member which responds to the temperature in the upper or warmer compartment. I illustrate, for example in Figure 2, a bulb 50 engaging or responsive to the temperature of the plate 37, which bulb, through a duct or tube 51, is adapted to control any suitable switch means not shown, for closing any suitable motor circuit, when cooling is called for, and for breaking such motor circuit when the upper compartment has been sufficiently cooled. The plates 25 of the lower compartment are preferably provided with the above described eutectic which provides a hold-over factor, and 75

insures against undesired increase in temperature. Since, when plate 37 calls for a refrigerant, the refrigerant must first pass through the plates 25, they are normally maintained at an adequately low temperature. If necessary a safety control may also be provided, including a bulb 50 in the lower compartment, and its associated tube 51, extending to any suitable switch for closing the motor circuit when the lower compartment B reaches a pre-determined maximum temperature. Under normal circumstances this is unnecessary.

It will be understood that area of the plate 37 is sufficient to maintain an adequate low temperature in the upper compartment A without at any time reducing the walls of the plate 37 to a temperature sufficiently low to cause frosting. The member 37, since it is a non-frosting cooling member, need never be defrosted.

In the use of the device, when the door 8 is opened for entry to the cold compartment B there will be a tendency to form frost on the forward ends of the plates 25. I find that by providing a substantial extension of the wall members 27 beyond the hollow part of the plates, 25 I in effect, provide a thin flange or fin, of substantial extension, beyond the eutectic filled hollow part of the plate. The temperature of the outer edge or part of the fin rises in relation to the temperature of the plate body proper, with a substantial reduction of the tendency to frost at the outer edges of the plate. This makes it unnecessary to scrape any excess frost from the plate edges, which would otherwise be deposited by, or be drawn from, the inflowing outside air.

I claim:

In a refrigerator, an insulating housing including walls defining and surrounding two separate storage compartments, said storage compartments each having an access aperture, insulating door means adapted removably to close said access apertures, and means for maintaining an above freezing temperature in one said compartment and a below freezing temperature in the other said compartment, including a horizontal plate in the low temperature compartment and a vertical plate in the high temperature compartment, said vertical plate being positioned to divide the high temperature compartment into two separate storage zones at opposite sides of said last named compartment, an air pervious partition closely adjacent each side of said vertical plate, and shelves supported between said air pervious partitions and the opposite sides of said high temperature compartment, and means for circulating a volatile refrigerant through said plates.
